(57) **CLAIM**

The ornamental design for a door with electronic lock for safe, as shown and described.

DESCRIPTION

FIG. 1 is a perspective view of a door with electronic lock for safe showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is another perspective view thereof, being mounted to a body of a safe.

A rear view thereof is omitted since it does not contain ornamental features. The dashed lines showing of the body
